UNITED STATES PATENT OFFICE

CHARLES NEWMAN, OF NEW YORK, N. Y., AND ERNST G. APPLETON, OF CHICAGO, ILLINOIS, ASSIGNEES TO BOACH-APPLETON MANUFACTURING COMPANY, OF CHICAGO, ILLINOIS, A CORPORATION OF ILLINOIS

ELECTRIC OUTLET RECEPTACLE

Application filed July 5, 1928. Serial No. 290,473.

The present invention relates to improvements in electric outlet receptacles.

More particularly the present invention relates to electric outlet receptacles such as are used in electric house wiring systems for receiving the electric wires and providing receptacles for the connections between said wires and the terminals of an electric fixture.

This application is a continuation as to common subject matter of an application filed by the same applicants on September 12, 1927, bearing Serial No. 218,933, for Electric outlet receptacles.

Commonly, the electric outlet receptacles which are in use provide mounting means for electric fixtures, and one of the objects of the present invention is to provide an electric outlet receptacle which provides an adjustable though rigid support for an electric fixture as well as a convenient support for the electric wires leading to said fixtures and the loom or conduit commonly used for protecting such wires.

A further object is to provide an electric outlet receptacle which is cheap to manufacture and which provides ready adjustability of the fixture supporting means.

A further object is to provide an electric outlet receptacle which is well adapted to meet the needs of commercial service.

Further objects will appear as the description proceeds.

Referring to the drawings—

Figure 1 is a view in front elevation of one embodiment of the present invention having secured thereto supporting ears which are shown in cooperative relationship with a wall stud;

Figure 2 is an end elevational view of the structure shown in Figure 1, the wall studs being omitted for purposes of clarity;

Figure 3 is a sectional view of an enlarged scale taken along the plane indicated by the arrows 3—3 of Figure 1;

Figure 4 is a sectional view taken along the plane indicated by the arrows 4—4 of Figure 1;

Figure 5 is a view of a blank which may be used in shaping up the box or receptacle shown in the preceding figures;

Figure 6 is a view in perspective of a preferred form of bridging member which may be used in the practice of the present invention; and

Figure 7 is a sectional view showing how an electric fixture may cooperate with the bridging member shown in Figure 6.

The numeral 10 indicates a wall stud, and the numeral 11 indicates a switch box supported upon said stud; box supporting ears 12—12 being provided for that purpose. The forward open face of the switch box 11 is flush with the outer face of the plaster, which outer face is indicated in Figure 7 by the numeral 13. The numeral 14 indicates an electric fixture or bracket. Such a bracket commonly includes a dished portion 15 adapted to rest upon the outer face 13 of the plaster and to hide from view the switch box 11 and adjacent parts of the plaster. Said fixture or bracket is also provided with the socket portion 16 for the reception of a commercial type of electric socket such as is commonly used for the reception of electric lamps, electric plugs and similar devices.

The receptacle is provided with knock-outs 17—17, through which electric house wires may be brought into the receptacle. Said electric house wires will be connected to an electric socket within the socket portion 16 of the bracket 14 through short connecting wires, in accordance with the usual practice.

According to common practice, sufficient slack will be provided in the wires extending from the switch box 11 to the electric device within the socket portion 16 whereby the necessary splicing may be accomplished and the slack wires hidden within the switch box 11. The brackets or fixtures 14 as commonly provided come in varying depths insofar as the dished portion 15 thereof is concerned. The present invention contemplates means whereby a bracket 14 may be supported by the switch box 11 throughout a relatively wide range of regions along said switch box and which will accommodate various depths of the bracket referred to.

Referring to Figure 5, the numeral 18 indicates a sheet metal blank having the substantially rectangular portion 19, bounded 100

by the broken lines 20—20. Outside of the broken lines 20—20 are the side wing portions 21—21 of the end wing portions 22—22. The side edges and said wing portions 21—21 and 22—22 are provided with fingers 23—23. Symmetrically disposed relative to certain of said broken lines 20—20 are the knock-outs 17, which in the illustrated embodiment of the present invention are of elongated form having rounded end portions. The wings 21—21 and 22—22 are adapted to be swedged out into substantially right-angular relationship with the portion 19 to form an electric outlet receptacle or switch box. The fingers 23—23 may be bent over adjacent walls, as illustrated in Figures 1, to hold said walls in rigid relationship with one another. When the wings 21—21 and 22—22 are bent up to form the receptacle 11, the portion 18 thus becomes the bottom wall of the receptacle, the wings 22—22 thus become the end walls of the receptacle, and the wings 21—21 become the side walls thereof. Each of the side walls 21—21 is provided with an elongated slot 24 parallel with and preferably equally spaced from the bottom wall 18.

The numerals 25—25 indicate clamping members having bowed portions 26—26 adapted to cooperate with a tubular conduit or loom enclosing the electric house wires. Screws 27 are provided, threaded into corresponding holes in the switch box 11, for holding said clamping members in clamping relationship with said loom or conduit.

35 The numeral 28 indicates a bridging member which in the illustrated embodiment of the present invention is of substantially U form, the parallel side legs 29—29 of which are spaced apart slightly less than the distance between the side walls 21—21 of the switch box 11. Extending from the extremities of the side legs 29—29 are the fingers 30—30 adapted to extend through the slots 24—24. As shown in Figure 4, said fingers 30—30 are adapted to be bent down into engagement with the side walls 21—21 whereby the bridging member 28 is slidably supported within the switch box 11.

The top portion of the bridging member 28 has the cantilever member or finger 31 projecting therefrom, which finger 31 lies in angular relationship with the adjacent side wall 21 of the switch box. Said finger 31 is provided with the screw-threaded aperture 32 adapted to receive the setscrew 33, which, as shown in Figure 4, lies in a line inclined to the adjacent side wall 21. By turning down the setscrew 33, a jamming relationship may be established between said setscrew 33, the adjacent side wall 21 and the adjacent leg 29, whereby the bridging member 28 may be rigidly secured against sliding movement. The bridging member 28 is preferably sufficiently wide to prevent swinging movement of said swinging member about the region of

contact of the setscrew 33 and the side wall of the receptacle. By reason of the construction illustrated and described, adjustment of the bridging member 28 longitudinally of the box or receptacle 11 is readily accomplished. 70

The central portion of the bridging member 28 is swedged outwardly to form a bell-shaped portion 34. The outer extremity of said bell-shaped portion 34 is provided with the tubular portion 35, which is interiorly 75 screw-threaded for the reception of the screw 36. Said screw 36 is adapted to extend through an aperture 37 in the bracket 14. The numeral 38 indicates an ornamental cap nut adapted to be screwed upon the screw 37 80 and to exert pressure on the outer side of the dished portion 15 of the bracket 14, whereby to hold said bracket firmly in position upon the wall.

It will be understood that the present invention provides a receptacle which may be rigidly secured in position upon a wall stud or the like, and which permits a very considerable range of adjustment of the electric fixture associated with said box in a direction longitudinally of said box. The present invention has the further advantage that brackets 14 having dished portions of varying depths can be securely mounted without the necessity of using screws 36 of different 95 lengths. Substantially all brackets with which applicants are familiar are dished to some extent, equal at least to the extent to which the tubular portion 35 of the bridging member 28 extends beyond the face 13 of the plaster. By reason of the provision of the swedged out portion 34 of the bridging member 28, the practical working range of a screw 36 of predetermined length is increased, it being possible by reason of the present invention to accommodate all wall brackets with which applicants are familiar with one length of screw 36 and still permit a cap nut 38 to exert pressure on the outer side of the wall bracket 14 to hold same rigidly against 100 the wall. 105

Though a preferred embodiment of the present invention has been described in detail, it will be understood that many modifications will occur to those skilled in the art. It is intended to cover all such modifications that fall within the scope of the appended claims. 115

What is claimed is—

1. In combination, an outlet receptacle having parallel opposed side walls and a bridging member extending across said receptacle, said bridging member having portions slidably supported by said side walls, said walls and said bridging member having interfitting portions disposed along lines parallel with the face of said receptacle for guiding said bridging member in a movement parallel with the face of said receptacle, said bridging member having a sufficiently close fit with said walls to guide said bridging member in 120 125 130

- a right line movement parallel with said walls.
2. In combination, an outlet receptacle having opposed side walls, said side walls being provided with slots extending parallel with the face of said receptacle, and a bridging member extending between said side walls, said bridging member having portions slidably disposed within said slots and having other portions adapted to engage said side walls to guide said bridging member in a right line movement in a direction parallel with said walls and with the face of said receptacle.
3. In combination, an outlet receptacle having opposed side walls, said side walls being provided with slots extending parallel with the face of said receptacle, and a bridging member extending between said side walls, said bridging member having portions slidably disposed within said slots, said bridging member having a sufficiently close fit with said walls whereby said side walls are adapted to guide said bridging member in a right line movement parallel with the face of said receptacle.
4. In combination, an outlet receptacle having opposed side walls, said side walls being provided with slots extending parallel with the face of said receptacle, and a bridging member extending between said side walls, said bridging member having portions slidably disposed within said slots, said bridging member having a sufficiently close fit with said walls whereby said side walls are adapted to guide said bridging member in a right line movement parallel with the face of said receptacle, said portions of said bridging member being bent over into substantially parallel relationship with the outer sides of said receptacle.
5. An outlet receptacle having parallel walls, a bridging member extending between said walls and supported thereby, said bridging member having leg portions disposed parallel with said walls and adapted to have sliding relationship relative thereto, said walls and said leg portions having portions for guiding said bridging member in a right line movement parallel with said walls and with the face of said receptacle.
6. An outlet receptacle having parallel walls, a bridging member extending between said walls and supported thereby, said bridging member having leg portions disposed parallel with said walls and adapted to have sliding relationship relative thereto, said walls and said leg portions having portions for guiding said bridging member in a right line movement parallel with said walls and with the face of said receptacle, and means carried by said bridging member for securing said bridging member in fixed position relative to said walls.
7. An outlet receptacle having parallel walls, a bridging member extending between said walls and supported thereby, said bridging member having leg portions disposed parallel with said walls and adapted to have sliding relationship relative thereto, said walls and said leg portions having portions for guiding said bridging member in a right line movement parallel with said walls and with the face of said receptacle, and a screw carried by said bridging member adapted to have jamming relationship between one of said walls and one of said leg portions for holding said bridging member in fixed relationship with said walls.
8. An outlet receptacle having parallel walls, a bridging member extending between said walls and supported thereby, said bridging member having leg portions disposed parallel with said walls and adapted to have sliding relationship relative thereto, said walls and said leg portions having portions for guiding said bridging member in a right line movement parallel with said walls and with the face of said receptacle, said bridging member having a struck up portion having a screw-threaded aperture, a screw in said aperture, the axis of said screw being angularly disposed relative to said side walls, said screw being adapted to jam against one of said side walls for holding said bridging member in fixed relationship relative to said side walls.
9. An outlet receptacle having parallel walls, a bridging member extending between said walls and supported thereby, said bridging member having leg portions disposed parallel with said walls and adapted to have sliding relationship relative thereto, said walls and said leg portions having portions for guiding said bridging member in a right line movement parallel with said walls and with the face of said receptacle, said bridging member having a struck up portion having a screw-threaded aperture, a screw in said aperture, the axis of said screw being angularly disposed relative to said side walls, said screw being adapted to have jamming relationship between one of said walls and one of said leg portions to hold said bridging member against sliding movement relative to said walls.
10. An electric outlet receptacle having a bridging member slidably supported by opposite parallel walls thereof, said bridging member having portions interfitting with said receptacle for guiding said bridging member in a right line movement parallel to said opposite walls and with the face of said receptacle, said bridging member having an intermediate portion thereof swaged outwardly, the outer extremity of said swaged portion being screw-threaded.
11. In combination, an electric outlet receptacle, an electric wall bracket supported thereby, said wall bracket having a dished

portion adapted to engage the wall of a building, said receptacle being provided with a bridging member secured to opposite walls thereof, said bridging member having a central portion thereof swedged outwardly, the outer portion of the swedged out portion being screw-threaded, and extending a material distance beyond the outer face of said receptacle, a screw disposed in said screw-threaded portion and extending through an aperture in said bracket, and a nut disposed upon said screw and exerting pressure upon the outer face of said bracket.

12. In combination, an outlet receptacle having opposed parallel walls, a bridging member slidably supported by said walls, said bridging member and said walls having interfitting portions for guiding said bridging member in a right line movement parallel to said walls and with the face of said receptacle, said bridging member having an upstruck cantilever portion and a setscrew threaded into said cantilever portion, said setscrew being adapted to have jamming relationship with one of said walls and with said bridging member.

13. A bridging member adapted for use in connection with an outlet receptacle having a U-shaped portion, the base of said U-shaped portion having a screw-threaded aperture therein, the legs of said U-shaped portion having outwardly extending bendable lugs.

14. A bridging member adapted for use in connection with an outlet receptacle having a U-shaped portion, the base of said U-shaped portion having a screw-threaded aperture therein, the legs of said U-shaped portion having outwardly extending bendable lugs, the base of said U-shaped portion having a member struck therefrom in angular relation to said base, said struck out member having a screw-threaded aperture extending therethrough.

45 Signed by CHARLES NEWMAN, at New York, New York, the 25th day of June, 1928, and by ERNST G. APPLETON, at Chicago, Illinois, this 26th day of June, 1928.

CHARLES NEWMAN.
ERNST G. APPLETON.
